ATTORNEY.

UNITED STATES PATENT OFFICE.

JULIUS BERBECKER, OF NEW YORK, N. Y.

DESIGN FOR CURTAIN-POLE.

SPECIFICATION forming part of Design No. 11,708, dated March 30, 1880.

Application filed January 26, 1880. Term of patent 7 years.

To all whom it may concern:

Be it known that I, JULIUS BERBECKER, of the city, county, and State of New York, have invented a new and original Design for 5 Curtain-Poles, of which the following is a full, clear, and exact description, reference being had to the accompanying drawing, making part of this specification, and which shows a front view of my curtain-pole.

10 This invention has reference to a design for a curtain-pole which is intended to imitate a plain pole and the rings by which the curtain is suspended; and the design consists of a curtain-pole having raised bands or imitation 15 rings provided with beads *a*, the intermediate portions between the bands being channeled or fluted. The terminal knobs of the pole are also provided with a raised imitation ring or band.

20 Referring to the drawing, *A* represents a curtain-pole, of any suitable material, which is provided with raised imitation rings or bands *B*, which are provided with beads *a*, as desired. The intermediate portions or panels, 25 *C*, of the pole are fluted or channeled in the longitudinal direction of the pole. The end knobs, *D*, are similarly channeled, and provided with a raised band or imitation ring, *D'*, which corresponds to the rings of the pole, 30 and imparts, with the flutings, a very striking and ornamental appearance to the pole.

Having thus described my invention, I claim as new and desire to secure by Letters Patent—

1. The design for a curtain-pole, having raised imitation rings or bands and fluted or channeled intermediate portions or panels, as shown and described.
2. The design for a curtain-pole, provided with raised imitation rings or bands, channeled or fluted portions or panels between the rings, and terminal knobs having raised rings or bands, as shown and described.
3. The design for a curtain-pole, consisting of fluted or channeled portions or panels and raised bands or imitation rings provided with beads, as shown and described.
4. The design for a curtain-pole, composed of fluted or channeled portions or panels, raised intermediate bands or imitation rings provided with beads, and of terminal knobs having raised bands with projecting beads, as shown and described.

In testimony that I claim the foregoing as my invention I have signed it this 13th day 55 of January, 1880.

JULIUS BERBECKER.
